END LINK FOR WATCH BANDS

Stanley Meyerson, 1350 Ocean Parkway,
Brooklyn 30, N.Y.

Filed May 23, 1963, Ser. No. 75,031

Term of patent 14 years

(Cl. D45—4)

FIG. 1

FIG. 2

FIG. 3

FIG. 1 is a top plan view of an end link for watch bands, showing my new design;

FIG. 2 is a side elevation; and

FIG. 3 is a section taken on the line 3—3 of FIG. 1.
I claim:

The ornamental design for an end link for watch bands, substantially as shown.
